US00D858506S

(12) **United States Design Patent** (10) Patent No.: **US D858,506 S**
Choi et al. (45) Date of Patent: ** Sep. 3, 2019

(54) **CASE FOR MOBILE PHONES**

(71) Applicant: **LG ELECTRONICS INC.**, Seoul (KR)

(72) Inventors: **Kyubong Choi**, Seoul (KR); **Hyunggon Ryu**, Seoul (KR)

(73) Assignee: **LG ELECTRONICS INC.**, Seoul (KR)

(**) Term: **15 Years**

(21) Appl. No.: **35/505,114**

(22) Filed: **Dec. 15, 2017**

(80) **Hague Agreement Data**

Int. Filing Date: **Dec. 15, 2017**

Int. Reg. No.: **DM/099123**

Int. Reg. Date: **Dec. 15, 2017**

Int. Reg. Pub. Date: **Jun. 15, 2018**

(30) **Foreign Application Priority Data**

Jun. 16, 2017 (KR) 30-2017-0027769

(57) **CLAIM**

The ornamental design for a case for mobile phones, as shown and described.

DESCRIPTION

1. Case for mobile phones

1.1 : Perspective

1.2 : Front

1.3 : Back

1.4 : Left

1.5 : Right

1.6 : Top

1.7 : Bottom

1.8 : Perspective view 2

1.9 : Reference view

The broken lines depict portions of the case for mobile phones that form no part of the claimed design; reproduction 1.1 is a front perspective view of the case for mobile phones; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; reproduction 1.8 is a back perspective view thereof; reproduction 1.9 is a reference view showing the design in use wherein the broken lines within the opening form no part of the claimed design.

1 Claim, 9 Drawing Sheets
